(57) **CLAIM**

The ornamental design for a set of fastners for locking a license plate, as shown and described.

DESCRIPTION

FIG. 1 is a perspective view of a set of fastners for locking a license plate showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The indicia or broken lines shown on the figures are for illustrative purposes only and are hereby disclaimed as forming no part of Applicant's claimed invention.
